UNITED STATES PATENT OFFICE

146,368

DESIGN FOR A ROLLER SHOE

James Edward McCaffrey, Los Angeles, Calif.

Application September 17, 1945, Serial No. 122,140

Term of patent 3½ years

(Cl. D34—14)

To all whom it may concern:

Be it known that I, James Edward McCaffrey, a citizen of the United States, residing at Los Angeles, in the county of Los Angeles, State of California, have invented a new, original, and ornamental Design for Roller Shoe, of which the following is a specification, reference being had to the accompanying drawing, forming part thereof.

Figure 1 is a side elevation of a roller shoe showing my new design; Figure 2 is a bottom plan of the roller shoe shown in Figure 1, showing my new design; Fig. 3 is a front elevational view of the roller shoe shown in Fig. 1, the rear fastening member being omitted for the sake of clarity; and Fig. 4 is a back end elevation of the roller shoe shown in Figure 1.

I claim:

The ornamental design for a roller shoe, as shown and described.

JAMES EDWARD McCAFFREY.
